UNITED STATES PATENT OFFICE

137,469

DESIGN FOR A MENU CARD

Lawrence Welk, Chicago, Ill.

Application June 23, 1943, Serial No. 110,506

Term of patent 14 years

To all whom it may concern:

Be it known that I, Lawrence Welk, a citizen of the United States, residing at Chicago, in the county of Cook and State of Illinois, have invented a new, original, and ornamental Design for Menu Cards, of which the following is a specification, reference being had to the accompanying drawing, forming part thereof.

Fig. 1 is a front elevational view of a menu card, showing my new design;

Fig. 2 is a right-hand side elevational view thereof; and

Fig. 3 is a top plan view thereof.

I claim:

The ornamental design for a menu card, as shown.

LAWRENCE WELK.
